MASONRY LINE BLOCK

Ralph Surratt, 5037 W. 38th Ave., Denver, Colo.

Filed Oct. 20, 1958, Ser. No. 53,039

Term of patent 3½ years

(Cl. D51—1)

Fig. 1.

Fig. 2.

Fig. 3.

Fig. 4.

I claim:

The ornamental design for a masonry line block, as shown and described.
